BLASTING CARTRIDGE

Filed Oct. 7, 1929

UNITED STATES PATENT OFFICE

FRANK H. ARMSTRONG, OF CHICAGO, ILLINOIS, ASSIGNOR TO SAFETY MINING COMPANY, OF CHICAGO, ILLINOIS, A CORPORATION

BLASTING CARTRIDGE

Application filed October 7, 1932. Serial No. 393,042.

The present invention relates to blasting cartridges of the type which consists of a metallic shell or body having an internal gas chamber, a pressure responsive discharge device and charging and charge energizing means. The latter means usually consists of a heat producing unit disposed within the gas chamber and arranged to be electrically activated, and for this purpose, the heater unit is arranged in circuit with the shell body and an electrode suitably insulated from the body. The gas charge may be introduced through a valve controlled passage in the electrode. In order to operate a cartridge of this character, the electrode and shell body are placed in circuit with a source of electricity.

The general object of this invention is to simplify the construction of cartridges of the type indicated with a view to securing increased reliability and minimizing service requirements.

More particularly, it is an object of the invention to provide an improved form of support for the heater unit, and an improved means of including the heater unit in circuit with the electrode and shell body.

Another object of the invention is to provide an improved means for connecting the electrode and shell body in circuit with a source of electricity.

Other objects and advantages of the invention will be noted in the following description of the accompanying drawings, wherein,

Figure 1 is a view in elevation showing the form of the assembled cartridge.

Figures 2 and 2A are views in longitudinal section, together showing the complete cartridge of the present invention, and

Figure 3 is a view in transverse section taken along line 3-3 of Figure 2.

The cartridge of the present invention consists generally of a substantially cylindrical body 1 having an internal gas chamber 2 which is open at one end of the body for discharge purposes. A rupturable disc 3 formed of mild steel or the like is employed to seal the discharge opening and for this purpose a shoulder 4 is provided in the shell body on which the disc is adapted to rest.

The disc is backed up by an anvil or shear ring 5 formed of hard steel and this ring is secured in place by means of the discharge cap 6 which is screw threaded into the end of the cartridge body and has its end in engagement with the shear ring. The discharge cap is provided with an axial passage 8 and a plurality of radial discharge ports 9. The cartridge so formed is adapted to be charged with a suitably compressed gas and may be discharged by means of a heat producing device capable of increasing the pressure of the gas charge to the rupture point of the disc 3.

The opposite end of the gas chamber 2 is defined by a transverse wall 10 which is provided with a central opening through which an electrode element 11 is positioned. Inwardly of the wall 10 there is formed a substantially cylindrical pocket 12 which communicates with the gas chamber and a portion of which is screw threaded as indicated at 13. The electrode 11 is provided with a flange 14 which is adapted to be positioned within the pocket 12 and to be clamped in such position by means of a nut 15 surrounding the reduced inner end of the electrode and engaging the inner face of the flange. The nut 15 is adapted to engage threads 14 formed in the cartridge body in order that a considerable pressure may be applied to the electrode in an axial direction to provide an effective seal between the radial surface of the flange 14 and the adjacent surface of the wall 10. The nut 15 is formed intermediate its ends with hexagon or other suitable surfaces to receive a wrench or the like for tightening the nut. The extreme inner end of the nut 15 is sufficiently reduced in diameter to permit the application of a socket wrench thereover and this reduced portion is preferably provided with screw threads as indicated at 17 to receive and support a heater cage 18. It will be observed that an end of the heater cage 18 is screw threaded for engagement with the thread formed on the inner end of the electrode nut. The heater cage is thus supported and extends axially into the gas chamber 2, but as will be seen in Figure 2A, the cage terminates short of the discharge opening in the end of

the cartridge. The form of the heater cage is best shown in Figures 2, 2A and 3 wherein it will be observed that the tube of which the cage is formed is provided with a plurality of elongated slots extending throughout a substantial portion of the length of the cage. The end of the cage remote from the electrode nut is partly closed by means of an inner sleeve 20 which may be welded or otherwise securely fastened to the cage proper. The sleeve 20 and the end of the cage with which it is associated, are so formed as to provide a conical end depression to facilitate the entering of a suitable turning tool. The tool may be in the form of a pin wrench and for this purpose the end of the cage 18 and sleeve 20 are provided with slots to accommodate the pins. In order to facilitate the assembly of the heater cage upon the electrode nut, the inner end of the nut is of conical form and the extreme end of the heater cage is also tapered inwardly in order that the heater may engage the end of the nut and automatically find its proper position thereon. The internal diameter of the heater cage is such that when the cage is resting on the inner wall of the gas chamber, the extreme inner end of the tapered portion of the electrode nut will lie within the end of the heater cage. By reason of this construction, it is merely necessary to move the heater cage longitudinally within the gas chamber and it will automatically engage the tapered surface of the nut and ride upwardly thereon until it becomes properly centered, at which time the cage may be rotated in order to engage the threads thereof with the threads of the nut.

A heater unit adapted for use in connection with the present heater cage and electrode is shown in the pending application in the name of L. E. Lawson, Serial No. 373,016, filed June 22, 1929. Structurally this heater unit comprises a tubular casing 21 which may be formed of paper or other suitable combustible material and metallic end closures 22 and 23. It will be noted that the closure 22 is applied over the end of the tube 21 whereas closure 23 is positioned entirely within the opposite end of the tube 21. These closures are preferably glued in place after the heater unit has been charged with the heat producing compound. It is to be understood, of course, that a suitable electrically operated igniting device is embedded in the heat producing compound of the heater and has its leads connected to the metallic closures 22 and 23. It will be noted that the heater unit can be inserted through one end only of the heater cage and that when a heater has been so inserted and the cage secured upon the electrode nut the metallic closure 22 has contact with the metal sleeve 20 and the metal of which the heater cage is formed and closure 23 surrounds and

has contact only with the inner end of the electrode 11. Attention is directed to the fact that by reason of the construction and arrangement of the closure 23 with reference to the non-metallic heater casing, it is impossible for this closure to make contact with any portion of the cartridge except the electrode. There is, thus, a circuit from the electrode through the heater to the heater cage and consequently to the electrode nut 75 and the body of the cartridge with which it is engaged. It will be understood, of course, that the electrode 11 is suitably insulated from the body of the cartridge and from the electrode nut as by means of insulating members 24, 25 and 26.

For the purpose of charging the cartridge with a suitable gas, the electrode is provided with an axial gas passage 34 which communicates with a transverse passage 35, leading 85 into the gas chamber 2. A valve body 27 is screw threaded on the outer end of the electrode and is insulated from the body of the cartridge by means of the fibre disc 28. A suitable nozzle opening 29 is provided in the 90 valve body 27 and this opening has communication with a passage 30 leading to the interior of the valve body. A valve stem 31 is adjustably engaged as by means of screw threads with the central portion of the body 95 and carries a soft metallic insert 33 for co-operation with the valve seat 32 surrounding the gas passage in the outer end of the electrode. By means of this construction a charging nozzle may be inserted in the opening 29 100 and by screwing the valve stem 31 outwardly to remove the inner end thereof from engagement with the electrode, gas is permitted to enter the interior of the valve body and pass through the electrode into the chamber 2. 105 When the desired amount of gas has been charged into the cartridge the valve stem 31 may be tightly screwed down into engagement with the end of the electrode to positively seal the passage therein and thus prevent escape of the charge. In order to avoid accidental discharge of the cartridge by stray electric currents or by accidental contact of the cartridge with power lines or the like, a device is provided whereby the electrode and cartridge body are effectively short circuited until such time as the cartridge has reached 110 its destination where it is to be discharged. This device consists of a plurality of sharp knife edge contacts 36 formed on the under side of the valve body and a sleeve 37 having an inwardly extending flange adapted to engage these contacts. The valve body is, of course, in electrical contact with the electrode only and the sleeve 37 is normally in electrical 115 contact only with the cartridge body through the medium of a metallic spring 38 which has one of its ends in engagement with the body and its opposite end in engagement with the inwardly extending flange of the sleeve. This 120 125 130

spring normally tends to urge the sleeve and its flange toward the contacts 36 to establish the short circuited condition and this condition prevails at all times when the firing or 5 terminal plug 39 is not in position in the end of the cartridge.

The firing or terminal plug 39 serves the two-fold purpose of connecting the two poles of a source of electricity to the electrode and 10 cartridge body respectively and operating the short circuiting device. This plug 39 has a detachable connection with the end of the cartridge body which is in the form of lugs and bayonet slots as indicated at 40 and 15 41. It will be observed from Figure 2 that the inner end of the plug is adapted to engage the end of sleeve 37 and move the same inwardly to a sufficient extent to break the contact between the points 36 and the flange 20 of the sleeve when the plug is positioned in the cartridge. The plug is provided with an opening 42 designed to receive a suitable conductor which may be secured in position by means of a set screw or the like as shown. A 25 metallic plug 43 is centrally positioned within a recess formed in the firing plug 39 but is insulated therefrom by means of the fibre disc 45 and fibre ring 44. The metallic plug 43 is provided with a central opening designed 30 to receive a second conductor which may be secured therein by means of a set screw. A metallic spring 46 extends between and electrically connects the plug 43 and the valve body 27. In this way the poles of a source 35 of current may be readily connected to the electrode and cartridge body.

Heretofore, cartridges of this general type have relied upon the establishment of electrical contact between opposite ends of the heater unit and the electrode and rupturable disc 40 respectively. This method of including the heater unit in circuit with the electrode and cartridge body has proven to be somewhat troublesome and inefficient due to the fact 45 that the distance between the electrode and the rupturable disc is precisely the same in all cartridges of a given type, whereas it has been found in practice that the heater units vary considerably in length. Also, there has 50 been some difficulty due to a poor contact or lack of contact between the rupturable disc and the adjacent end of the heater. The present arrangement of the heater and supporting cage therefor is regarded as an important improvement over the old method in 55 that the heater need not be made of sufficient length to extend the entire distance from the electrode to the rupturable disc, and may therefore be made of any desired diameter 60 to accommodate the amount of heat producing compound required. The present arrangement has also been found very advantageous in that both contacts of the heater are in effect made adjacent the same end of 65 the cartridge. In other words, one end of

the heater contacts with the electrode and the other end thereof has electrical connection with the electrode nut which immediately surrounds the electrode and connects with the cartridge body adjacent to the electrode. It will be noted that the heater cage 70 may be so adjusted upon the threaded portion of the electrode nut as to accommodate substantial variations in heater dimensions, thus insuring contact in all cases and without 75 danger of disrupting the heater tube or damaging its contacts.

I claim:

1. A blasting cartridge comprising a metallic body having an internal gas chamber, 80 an electrode extending through an opening in said body and into said chamber, a member surrounding said electrode within the chamber and having connection with said body, means for insulating said electrode from said body and member, and an electrically energizable heater unit having terminals connecting with said electrode and member respectively. 85

2. A blasting cartridge comprising a metallic body having an internal gas chamber, 90 an electrode extending through an opening in said body and into said chamber, a member surrounding said electrode within said chamber and having connection with said body, 95 means for insulating said electrode from said body and member, a heater cage supported by said member, and an electrically energizable heater unit disposed within said cage, said heater unit having terminals connecting with said electrode and cage respectively. 100

3. A blasting cartridge comprising a substantially cylindrical metallic body having an internal gas chamber, a pressure responsive discharge device associated with one end of said body, an insulated electrode associated with the other end of said body, an electrically energizable heater disposed within said chamber and having contacts, one of which is adapted to have electrical connection with said electrode, and means for electrically connecting the other contact with said body at a point adjacent said electrode. 105

4. A blasting cartridge comprising a metallic body having an internal gas chamber, 110 an electrode associated with one end of said body and insulated therefrom, a heater unit having contacts, and means for connecting said contacts with said electrode and body respectively at said end. 115

5. A blasting cartridge comprising a metallic body having an internal gas chamber, a pressure responsive venting device associated with said body and chamber at one end thereof, an electrode extending through said body 120 and into said gas chamber adjacent the opposite end thereof, means for insulating said electrode from said body, a nut surrounding said electrode and having threaded engagement with the interior of said body, means 125

for insulating said nut from said electrode, a heater support secured to said nut, and a heater carried by said support and having electrical contact at its opposite ends with said 5 electrode and heater support respectively.

6. A blasting cartridge comprising a metallic body having an internal gas chamber, said body having a circular opening through a wall thereof and a cylindrical 10 pocket adjacent said opening on the interior of said body and communicating with said chamber, an electrode positioned in said opening and extending on opposite sides of said wall, a radial flange on said electrode and disposed within said pocket, an insulating and sealing member interposed between the end wall of said pocket and one face of said flange, means surrounding said electrode and insulated therefrom and acting against the 15 other face of said flange for effecting the sealed relation, a heater support carried by said means, and a heater carried by said support and having electrical contact with said electrode and support respectively.

25 7. A blasting cartridge comprising a metallic body having an internal gas chamber, an electrode extending through a wall of said body and into said chamber, insulating means between said electrode and body, a gas 30 passage extending through said electrode, a valve cap secured to the outer end of said electrode, a valve carried by said cap and adapted to cooperate with said passage, and a movable member having electrical connection with said body and adapted to normally engage said cap to provide a short circuit between said electrode and body.

8. A blasting cartridge comprising a metallic body having an internal gas chamber, an electrode extending through a wall of said body and into said chamber, insulating means between said electrode and body, a gas passage extending through said electrode, a valve cap secured to the outer end of said 45 electrode, a valve carried by said cap and adapted to cooperate with said passage, and a movable member having electrical connection with said body and adapted to normally engage said cap to provide a short circuit between said electrode and body and a detachable plug having means for connecting said electrode and body respectively with the respective poles of a source of current and operable when applied to break said short 55 circuit.

9. A blasting cartridge comprising a metallic body having an internal gas chamber, an electrode extending through a wall of said body and into said chamber, insulating means 60 between said electrode and body, a gas passage extending through said electrode, a valve cap secured to the outer end of said electrode, a valve carried by said cap and adapted to cooperate with said passage, a plurality of 65 relatively sharp contact elements on said cap,

a movable member having electrical connection with said body and adapted to normally engage said contacts to provide a short circuit between said electrode and body, and means for breaking the short circuit. 70

10. A blasting cartridge comprising a metallic body having an internal gas chamber, an electrode extending through a wall of said body and into said chamber, insulating means between said electrode and body, a gas passage extending through said electrode, a valve cap secured to the outer end of said electrode, a valve carried by said cap and adapted to cooperate with said passage, a plurality of relatively sharp contact elements on said cap, a sleeve surrounding said cap and having an inwardly extending flange adapted to engage said contacts, a spring interposed between said flange and the body for normally urging said flange toward said contacts, and a plug as having detachable engagement with said body and adapted to engage and move said sleeve out of contacting position. 75

11. A blasting cartridge comprising a metallic body having an internal gas chamber, a pressure responsive venting device associated with said body and chamber at one end thereof, an electrode extending through said body and into said gas chamber adjacent the opposite end thereof, means for insulating said electrode from said body, a nut surrounding said electrode and having threads on one end for engagement with the interior of said body, means for insulating said nut from said electrode, said nut having threads on the opposite end thereof, a heater support engaging said threads, and a heater carried by said heater support and having electrical contact with said support and electrode, respectively. 80

12. A blasting cartridge substantially as set forth in claim 11, further characterized in that said nut is provided with a wrench engaging portion intermediate the threads on opposite ends thereof. 105

Signed at Chicago, Illinois, Cook County, this 3rd day of October, 1929.
